UNITED STATES PATENT OFFICE.

ALFRED C. NELSON, OF LAKEWOOD, OHIO, ASSIGNOR TO THE WILLIAM B. POLLOCK COMPANY, OF YOUNGSTOWN, OHIO, A CORPORATION OF OHIO.

LADLE-TILTING MECHANISM.

Application filed August 6, 1921. Serial No. 490,243.

To all whom it may concern:

Be it known that I, ALFRED C. NELSON, a citizen of the United States, residing a Lakewood, in the county of Cuyahoga and 5 State of Ohio, have invented certain new and useful Improvements in Ladle-Tilting Mechanisms, of which the following is a specification.

My invention is particularly advantageous for use in connection with hot metal ladles such as are used for transporting molten metal or slag in and about blast furnace and other iron and steel manufacturing plants.

15 In the preferred embodiment of my invention, I provide a flexible or articulated tilting member such as a rope or chain which is suspended near its ends by suitable supports provided upon opposite sides of the 20 ladle in its tilting plane. The tilting member loosely encompasses or girdles the bottom of the ladle so as to have enough slack in it to permit one of its ends to be lifted on or off its support, and is unwound from 25 the surface of the ladle as it is tilted for pouring and then rewound upon the ladle as it again assumes its upright position.

The tilting member is also provided with a suitable eye in its end or is otherwise adapted 30 to be engaged by a crane hook. The tilting member is so constructed and supported that the crane hook engaging means is always presented in the proper direction to receive the nose of the crane hook as it is 35 brought into position for engagement. Preferably the eye of the tilting member is presented outwardly of the side of the ladle, so as to readily receive the nose of the crane hook when it is approaching the side of the 40 ladle in the tilting plane of the ladle. When one end of the tilting member is engaged by a crane hook, and the crane is operated to hoist, the slack in the flexible member will 45 first be taken up and the end of the tilting member will be lifted above its support upon the ladle so as to clear the support when the ladle is turned on its trunnions to be poured.

Conversely, when the crane is operated to lower and the ladle has tilted back into its 50 normal upright position, the tilting member will again be engaged by the support on the ladle and be suspended thereon while the crane hook is further lowered and moved away from the ladle. Except while the ladle 55 is being tilted, the flexible member is not in

close contact with the hot shell of the ladle and is therefore not damaged by overheating.

Among the objects of my invention are the provision of a ladle tilting device which requires no manual labor for its attachment to the ladle or for its operation; the provision of a tilting member which may be secured to or supported upon the ladle in such a manner that the hook of the crane employed for tilting the ladle may be made to engage with the tilting member without hand guiding or other manipulation by the floor man; the provision of a simple, reliable and safe ladle tilting device; the provision of a ladle tilting device which is always carried by the ladle and available for instant use; the provision of a ladle tilting device which may be readily used for tilting large hot metal ladles for either short 75 or long pours when the ladle is supported upon a ladle car or when the ladle is supported by a traveling crane. These and other objects are accomplished by the use of my invention which is described in these 80 specifications and shown in the accompanying drawings in which—

Fig. 1 is a side elevation of a hot metal ladle car carrying a ladle equipped with my invention;

Fig. 2 is an enlarged fragmentary elevation of the clevis and rope eyes;

Fig. 3 is a fragmentary vertical section on line III—III of Fig. 2;

Fig. 4 is a transverse vertical section on line IV—IV of Fig. 1 with the ladle shown in dot and dash lines being tilted for a “short pour”;

Fig. 5 is a transverse vertical section on line IV—IV of Fig. 1 with the ladle shown in dot and dash lines being tilted for a “long pour”;

Fig. 6 is a side elevation, Fig. 7 is a longitudinal section and Fig. 8 is an enlarged view of the rope end of a preferred 95 form of flexible member which may be employed in my invention;

Fig. 9 shows a ladle removed from the ladle car and supported by crane hooks while it is being tilted by a mechanism embodying my invention;

Fig. 10 is a fragmentary side elevation of a hot metal ladle car having drop side frames the ladle being equipped with a tilting device embodying my invention; and

Fig. 11 is a vertical section on line XI—XI of Fig. 10.

Referring to the drawings 1 represents a hot metal ladle car having straight side frames such as the car shown and described in my application Serial No. 397,285, filed July 19, 1920, issued January 31, 1922, as Patent No. 1,405,065. Upon the car, 1, the ladle, 2, is supported by trunnions, 3, 3, which rest in suitable bearings, 4, 4, which are carried by the car. 5, 5, are lifting trunnions which are adapted to be engaged by suitable hooks for lifting the ladle bodily from the car. The ladle, 2, has its bottom portion rounded as shown at 6 so that when it is tilted it will clear the straight side frame sills, 7, 7, of the car body. Firmly secured to the body of the ladle, 2, upon either side so that the ladle may be tilted in either direction are brackets, 8, 8, each of which is provided with a pair of spaced apart thumb like projections or hooks, 9, 9, in which there is formed a seat, 10, for the pin, 11, to which pin an end of the tilting member, 12, is secured. The pin, 11, is removably mounted in a clevis, 13, by suitable means such as the key plates, 14, which fit in shallow, transverse slots, 15, in pin, 11, and are secured to the clevis, 13, by means of cap screws or bolts, 16.

The sides of the clevis, 13, are connected together by a preferably integral cross bar, 17, which is adapted to be engaged by a lifting hook such as is shown in dot and dash lines at 18 in Fig. 4. The clevis, 13, thus becomes a part of the tilting member, which may be said to be articulated at the pivot pin, 11. It will be observed that when the ladle is in an upright position, for instance as shown in full lines in Fig. 4, the upper part of the clevis, 13, falls away from the side of the ladle until arrested by the lower end, 13^a, contacting with the side of the ladle. The lifting eye of the clevis formed by the sides, 13, and bar, 17, is thus inclined away from the ladle, so as to readily receive the nose of an upwardly moving crane hook. The lower end, 13^a, of the clevis acts as a stop to prevent the clevis from overturning too far about the pin, 11.

I prefer to employ a flexible tilting member made of a plurality of ropes of equal lengths, such as shown in Figs. 6, 7 and 8, each of the ropes having an eye formed in each end by bending the rope about a thimble, 19, and splicing the end into the body of the rope as shown at 20. When made in this manner ample strength and accurate length are assured and the ropes may be readily assembled upon pins, 11, by first withdrawing the pins from the clevises after removing the key plates, 14, then placing the eyes of the ropes in position in the clevises, 13, reinserting the pins, 11, and again securing the key plates, 14, in position to

retain the pins, 11, in the clevises. The flexible member, 12, is made sufficiently longer than the girth of the bottom of the ladle to loosely encompass it so as to provide enough slack to permit the pin, 11, to be lifted over the thumb, 9, and automatically drop into the seats, 10, formed in the thumbs, 9, when the clevis is brought close to the body of the ladle. When thus constructed it is unnecessary for the flexible member or the clevis, 13, to be lifted by hand or other means in order to place it upon or detach it from the crane hook. For instance, upon lowering the ladle from its tilted position shown in dot and dash lines in Figs. 4, 5 and 9, to upright position, the rope, 12, will be wrapped about the bottom of the ladle, the pin, 11, will swing over the thumbs, 9, close to the body of the ladle above the seats, 10, the pull of the crane taking the slack out of rope, 12; and then as the crane hook is lowered further and the pull on rope, 12, is relieved the pin, 11, will automatically drop into the seats, 10, which will support the clevis, 13, and thereby support the flexible member, 12, against further downward movement. The crane hook will now lower out of contact with the cross bar, 17, and may be moved away from the ladle by the crane man without any attention from the floor man.

In Fig. 4 the ladle car is shown standing upon the track rails, 21, while the ladle, 2, as shown in dot and dash lines is being tilted about the short pour stands, 22, to pour the contents of the ladle close to the side of the car.

In Fig. 5 the ladle car is shown standing upon the track rails, 21, while the ladle as shown in dot and dash lines is being tilted about its right hand trunnion, 3, for making a "long pour" thus delivering the metal at a greater distance from the side of the car than when tilted for a "short pour" as shown in Fig. 4.

In Fig. 9 the ladle, 2, is shown supported by the crane hooks, 23, as having been lifted bodily off from the ladle car and the ladle is being poured into a charging trough, 24, such as is used when charging open hearth furnaces such as that conventionally shown at 25.

In Figs. 10 and 11 the ladle, 26, is shown mounted upon a drop frame car whose side frame members, 27, are "dropped" or depressed as shown at 28, to permit the ordinary flat bottom ladle to clear them when the ladle is tilted. In this application of my invention one end, 29, of the tilting member, 30, is shown permanently secured to a bracket, 31, upon one side of the car while the other end, 32, of the tilting member, 30, is detachably supported upon a bracket, 8, which is similar to the brackets shown in the other figures of the drawings. This con-

struction may be employed when the ladle has to be tilted in only one direction.

To prevent the flexible members from slipping out of place I prefer to provide guides, such as the flanged brackets shown at 33, upon the corners of the ladle, 26, as in this form of ladle the bottom is ordinarily circular and the flexible member tends to slip out of position upon the rather abrupt corner where the bottom joins the side of the ladle unless some provision such as that shown at 33 for retaining the flexible member is made.

The operation of my invention as will be understood from the foregoing description is as follows—the ladle being equipped with my invention, for instance as shown in the drawings, when it is desired to tilt the ladle the crane operator lowers the crane hook to the proper height to engage the bar, 17, of the clevis, 13, and moves the crane hook toward the ladle until the point of the hook enters the opening in the clevis below the bar, 17. He then causes the hook to rise into engagement with the bar, 17, and tilts the ladle in the manner described. After the ladle has been poured the crane operator lowers the crane hook until the pin, 11, drops into the seats, 10, provided upon the bracket, 8, and the weight of the flexible member, 12, and its clevis, 13, is supported by the thumbs, 9. Further lowering of the hook causes it to be disengaged from the clevis, 13, after which the hook may be moved away. It requires no more than ordinary skill upon the part of the crane operator to thus operate my improved tilting mechanism.

The use of my invention eliminates the necessity of employing a man to attach and detach a chain, rope or other tilting device to the ladle or to attach the tilting device to the crane hook, which operations, as is well known, are arduous, difficult and dangerous on account of the great heat which is radiated from the hot metal in the ladles. My improved tilting device is always carried by the ladle and is ready for immediate use, whereas, when detached ropes, chains or hooks are employed they are frequently not at the place they should be for convenient use when required. For large capacity ladles the weight of the detachable tilting connection is too great for a man to handle, and my invention is therefore particularly advantageous for such ladles. The flexible member of my tilting device is carried in such a manner that it is not liable to become twisted or kinked when not in operation and its useful life and its ability to perform its severe duty are consequently prolonged and assured.

It will be apparent to those skilled in the art that the flexible member may be constructed in a variety of ways and I do not limit my invention to the form of flexible

member shown and described herein. Neither do I limit my invention to the particular supporting means for the ends of the flexible member upon the sides of the ladle shown in the drawings, nor to the particular manner or means by which the end of the flexible member is adapted to be engaged by a crane hook.

It is essential only that the tilting member have one of its ends secured to the ladle and its other end detachably supported by the ladle, the tilting member encompassing a portion of the periphery of the ladle in the tilting plane thereof so that the tilting member will be unwound as the ladle is being tilted for pouring and then be rewound as the ladle is allowed to again assume its upright position. It is obvious that the portion of the periphery of the ladle encompassed by the tilting member need be only so much as is needed to give the tilting member the desired leverage for holding the ladle in its maximum tilted position.

Having thus described my invention, I claim:

1. The combination of a ladle, brackets secured to opposite sides of said ladle and a flexible member loosely encompassing the bottom of said ladle and having its ends supported, one of them detachably, by said brackets.

2. The combination of a ladle, brackets secured to opposite sides of said ladle, a flexible member loosely encompassing the bottom of said ladle having its ends supported, one of them detachably, by said brackets, said detachably supported end being adapted to be engaged by a crane hook.

3. The combination of a ladle, brackets secured to said ladle at spaced apart points in the plane in which the ladle is tilted, and a flexible member loosely encompassing the bottom of said ladle and having its ends supported, one of them detachably, by said brackets.

4. The combination of a ladle, brackets secured to opposite sides of said ladle, a flexible member loosely encompassing the bottom of said ladle and having its ends supported, one of them detachably, by said brackets, said detachably supported end being provided with an eye adapted to be engaged by a crane hook.

5. The combination of a ladle, brackets secured to opposite sides of said ladle, a flexible member loosely encompassing the bottom of said ladle, having its ends supported by said brackets, one of said ends being detachably supported by one of said brackets and provided with an eye adapted to be engaged by a crane hook, said flexible member being constructed and supported to present said eye outwardly of the side of said ladle.

6. The combination of a ladle, brackets se-

cured to opposite sides of said ladle, a flexible member loosely encompassing the bottom of said ladle and having an eye in each end and lateral projections adjacent to said eyes, said projections being adapted to engage said brackets to support said flexible member.

7. The combination of a ladle, brackets secured to opposite sides of said ladle, said brackets having spaced apart projections forming pin-bearings, a flexible member provided with an eye in each end, cross pins secured to the ends of said flexible member inside said eyes, said flexible member being adapted to loosely encompass the bottom of said ladle between said brackets and said pins being adapted to rest in said pin bearings in said projections to support said flexible member.

8. The combination of a ladle, a bracket secured to one side of the ladle, a flexible member having one of its ends secured to said bracket, said flexible member extending loosely under the bottom of the ladle, a second bracket secured to the other side of the ladle, said second bracket being provided with a projection extending outwardly from said ladle, the free end of said flexible member being provided with means adapted to be engaged by a lifting hook said means being also adapted to be supported by said projection.

9. The combination of a ladle, a flexible member provided with a crane hook eye in each end, two brackets secured one on either side of said ladle, means for supporting said flexible member on said brackets to present said crane hook eyes outwardly of said ladle, said brackets having upturned projections, said flexible member being of such a length that when its ends are supported on said brackets the flexible member will hang loosely under said ladle to permit of its being lifted off from its support on one of said brackets.

10. The combination of a ladle, two brackets secured one on either side of said ladle, one of said brackets having an upturned projection forming a hook extending outwardly and upwardly from the side of said ladle, a flexible member having a crane hook eye in one of its ends, supporting means connected to said flexible member for supporting it on said hook to present said crane hook eye outwardly from the side of said ladle, the other end of said flexible member being secured to the other of said brackets, said flexible member being of a length, when thus mounted on said ladle to permit said supporting means to be lifted on and off said hook.

11. The combination of a ladle having

trunnions about which it is adapted to be tilted for pouring, said ladle having two projections on its outer shell in the plane of its tilting movements, said projections being adapted to support a flexible member, a flexible member having its end adapted to be hung upon said projections, said flexible member being thus supported upon said projections and loosely encompassing the ladle between said projections to provide enough slack to permit one end of said flexible member to be lifted on and off its support, this end of said flexible member being also adapted to be engaged by a crane hook.

12. The combination of a ladle, a tilting member loosely encompassing a portion of the periphery of the ladle in the tilting plane thereof, said tilting member having one end attached to the ladle the other end of said tilting member being free, and means on said ladle detachably supporting said free end of said tilting member in position to be engaged by a crane hook.

13. The combination of a ladle having trunnions about which it is adapted to be tilted for pouring, tilting means secured to the ladle encompassing a portion of the periphery thereof in its tilting plane, said tilting means having a free end adapted to be engaged by a crane hook, said tilting means being adapted to be unwound from the surface of the ladle as it be being poured and rewound upon the surface of the ladle as it returns to its upright position, and means for supporting the free end of said tilting means in position on said ladle to be engaged by said crane hook.

14. The combination of a ladle, a tilting member having one end secured to said ladle and its other end detachably supported thereon, said tilting member encompassing a portion of the periphery of said ladle in a tilting plane thereof.

15. The combination of a ladle, a tilting member having one end secured to said ladle and its other end detachably supported thereon, said tilting member encompassing a portion of the periphery of said ladle in a tilting plane, thereof, and guiding means for said tilting member on said ladle.

16. A ladle provided with hooks upon its opposite sides, a flexible member having its ends respectively supported by said hooks and loosely encompassing the bottom of the ladle so as to provide enough slack in the flexible member to permit one of its ends to be lifted off from its hook, the flexible member having one of its ends adapted to be engaged by a lifting hook.

In testimony whereof I affix my signature.

ALFRED C. NELSON.
